UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed August 23, 1919. Serial No. 319,490.

To all whom it may concern:

Be it known that I, ALFRED G. F. KUROWSKI, a citizen of the United States, formerly a citizen of Germany, residing in Brooklyn 5 Borough, in the county of Kings, city and State of New York, have invented certain new and useful Improvements in Typewriting Machines, of which the following is a specification.

10 This invention relates to the type-keys of typewriting machines. Such keys include a paper on which is printed the designation of the type or types controlled by the particular key, and a glass cover serving to 15 protect the paper. In some instances, it may be desirable to change the type papers so as to substitute others bearing different characters, or to substitute blanks. This invention, therefore, has for an object such improvement in the construction of a type-key 20 that the key-paper thereof may be changed by an operative who is unskilled in mechanics by an extremely simple manipulation.

25 A feature of the invention consists in the provision of a key-cup of usual construction surmounted by a key-ring which loosely engages the cup, and which is detachably secured thereto. Preferably the securing 30 means consists of a spring clip or locking member, under the cup, and provided with portions which resiliently seat into a groove formed in the flange of the ring, which projects downwardly below the bottom of the 35 cup, the clip having other portions engaging the under side of the key-cup to prevent the ring from being lifted off the cup when the clip is in place. Finger-pieces depend, under the cup, from the clip to enable 40 it to be sprung to release its locking portions from the ring groove so that the ring may be readily lifted from the cup.

Other features and advantages will hereinafter appear.

45 In the accompanying drawings,

Figure 1 is a perspective view of the invention.

Figure 2 is a perspective view of the parts constituting my improved key-top, said 50 parts being separated to better show their manner of co-operation.

Figure 3 is a sectional view.

Figure 4 is a bottom plan view.

Figure 5 is a perspective detail of the 55 spring clip or locking member.

Referring to the drawings, a key-stem 1 has mounted upon it the usual key-cup 2, said cup having the usual rectangular shank forming a socket which tightly fits over the upper portion of the key-stem, said cup 60 also having the usual under side or bottom, as shown in the drawings, and the usual flange 3 forming the cup, and within said flange are held the key-paper 4 and the glass protecting cover 5.

65 A key-ring 6 surmounts the key-cup, this ring having a turned-over top flange 7 and a side flange 8. The inturned top flange 7 is turned downward at its edge for securely and firmly retaining the usual key-paper and 70 glass cover. The side flange 8 is provided in its lower margin with an inner annular or circumferential groove 9 preferably formed by striking out the sides of the metal forming the ring, said groove occupying a 75 position substantially in the plane of the under side of the key-cup, by reason of the flange or skirt 8 of the key-ring projecting downwardly below the bottom of the cup. In order to detachably secure the ring to the 80 cup, there is provided a manually-releasable spring clip or locking member 10, shown in the drawings as a resiliently expansible wire split-ring, forming an expansible catch-device under the cup. This member is formed 85 as shown in Figures 4 and 5, and is provided with outwardly-projecting locking portions 11 which seat into the groove 9 of the key-ring, said clip also being provided between the projections 11 with inner portions 12 90 free of said groove and which engage the under side or bottom of the cup, so that when the spring clip or locking member is in normal position it presents the appearance shown in Figure 4. This spring clip is also 95 provided at its ends with a pair of depending spaced fingers 13, which project downwardly under the cup, and by which the clip is manipulated when it is desired to remove the ring from the cup, by squeezing 100 together the finger-pieces 13 for contracting the catch-device to disengage or withdraw the locking projections 11 from the groove 9. It will be readily understood, of course, that, as soon as the locking portions 11 are 105 disengaged from the groove, the ring may be lifted off the cup and the key-paper changed or entirely removed, as desired.

With the construction described, no tool is necessary to remove the key-ring, and no 110

mechanical skill is necessary in performing the operation.

Variations may be resorted to within the scope of the invention, and portions of the 5 improvements may be used without others.

Having thus described my invention, I claim:

In a typewriting machine, a type-key comprising an open-top cup having a bottom 10 and an upstanding marginal flange, a key-paper loosely contained in the cup and overlying the bottom thereof, a cover-glass loosely contained in the cup and resting on the key-paper, a ring having a skirt 15 removably fitting over the marginal flange of the cup from the top and provided at its top with an inturned flange to engage the margin of the cover-glass to hold the cover-glass and the key-paper in the cup, 20 said skirt having a lower marginal portion

projecting downwardly below the bottom of the cup and provided with an internal annular groove, a spring-wire expansible catch-device under the cup and having projections to engage in said groove and having portions 25 between said projections free of said groove and engaging the bottom of the cup, so as to retain the ring on the cup, and a pair of spaced finger-pieces carried by the catch-device and projecting therefrom downwardly under the cup to be squeezed together for contracting the catch-device to disengage said projections from said groove, to enable the ring to be lifted off the cup for changing the key-paper.

ALFRED G. F. KUROWSKI.
